Primary Examiner—Ralf Seifert

(74) *Attorney, Agent, or Firm*—Mark W. Croll; Paul F. Donovan

(57) **CLAIM**

The ornamental design for a buckle, as shown and described.

DESCRIPTION

FIG. 1 is a perspective view of the buckle showing the new design;

FIG. 2 is a side view thereof;

FIG. 3 is an opposite side view thereof;

FIG. 4 is an end view thereof;

FIG. 5 is an opposite end view thereof;

FIG. 6 is a top view thereof; and,

FIG. 7 is a bottom view thereof.

The broken line showing of an opening is included for the purpose of illustrating environmental matter and forms no part of the claimed design.
